WITHDRAWABLE SUCKER ROD ASSEMBLY

William H. Stigall, Taft, Calif.

Application August 11, 1936, Serial No. 95,469

3 Claims. (Cl. 255—28)

This invention relates to pumping wells, and in particular to the type comprising a reciprocating sucker rod assembly of the valved type operating within a casing, and by way of comparison with prior art devices, the novelty resides chiefly in an especially constructed sectional sucker rod assembly, the major portion of which is susceptible of being withdrawn from the casing if and when the valve becomes sanded and stuck in place.

Stated otherwise, the invention in particular is used in conjunction with sucker rods in pumping wells and provides a positive means for releasing the rod from the pump when the pump becomes sanded or the standing valve stuck, making it substantially impossible to "pull the pump". The incorporation of the invention in the substantially otherwise standardized assembly makes it possible to release the rod from the pump without the danger of loosening any sucker rod joints above the release device, since the releasing action is accomplished by turning the rod in a right-hand or clock-wise direction simultaneously tightening all of the joints with the exception of the releasable special joint forming a part of the arrangement.

It is a matter of common knowledge that when a pump is ordinarily being pulled, many of the sections of the sucker rod are apt to become accidentally disconnected and drop into the well casing, causing the tubing and sometimes the casing to part. This necessitates resorting to expensive fishing jobs. The common method now in use in unscrewing rods is by turning them to the left or anti-clockwise which gives them a chance to break at each joint or approximately every 30 feet. Thus is created a hazard of rods and other accompanying disadvantages. The use of the present invention makes it possible to remove substantially all of the rods or sections in the sucker rod assembly by simple separable means, thus saving two or three hours' time on each stripping job according to the depth of the well.

Briefly described, the preferred embodiment of the invention comprises latch-equipped separable joint means located just above the valve at the bottom of the well, said means coming automatically into play when the entire sucker rod, as a unit, is turned in a clockwise direction whereby to allow all of the rod sections above said latch-equipped joint to be satisfactorily pulled.

Other features and advantages will become more readily apparent from the following description and drawings.

In the drawings, wherein like numerals are employed to designate corresponding parts throughout the views:

Figure 1 is a view partly in section and partly in elevation showing a well casing and reciprocating pump or sucker rod assembly embodied therein and including the improved automatically releasable coupling or joint.

Figure 2 is a view showing the disconnectible parts of the coupling or joint separated.

Figure 3 is an elevational view of the double oppositely threaded member forming an important part of the latch-equipped coupling or joint.

Figure 4 is a top plan view of the part shown in Figure 3.

Figure 5 is a longitudinal sectional view through the double threaded upper section or member of the joint structure.

Figure 6 is a top plan view of said upper section, that is, the part shown in Figure 5.

Figure 7 is a perspective view of the T-shaped latch or key.

Figure 8 is an enlarged sectional and elevational view showing the parts and the key or latch in its normal part-locking position.

Figure 9 is a longitudinal section through the right hand threaded lower member or section of the releasable joint structure.

Figure 10 is a sectional view of the spring accommodation or adapter cup.

Figure 11 is an elevational view of the latch thrust or operating member.

Figure 12 is a cross-section taken approximately on the plane of the line 12—12 of Figure 8.

Attention is first invited to Figure 1 wherein it will be observed that the pump or well casing is denoted by the numeral 13. This part is of conventional form. So is the so-called sucker rod assembly 14. That is to say, this is of the reciprocating type and serves to operate a traveling valve at the bottom of the well (not shown).

As is customary, it is composed of a plurality of sections 15 which in the present instance are all joined together by right hand screw threads.

The only exception to this is the left hand screw threads appearing as a part of special automatically releasable coupling or joint means unitarily denoted by the numeral 16. This means 16 comprises an internally screw-thread lower coupling member or sleeve 17 which is shown in Figure 9 and is provided with right hand screw threads 18.

Threaded into this is the correspondingly threaded head 19 of the thrust rod 20 which is in effect a trip member. This has right hand threaded connections 21 with a suitable union 22.

which in turn connects with the operating means for the reciprocatory valve (not shown).
 The right hand screw-threaded extension 23 on the lower end of the intermediate section or part 24 of the joint structure threads into the upper correspondingly threaded end of said sleeve 17 as shown in Figure 8. This part 24 is longitudinally bored to accommodate the rod or stem 25 of the T-shaped latch. The upper head 26 on the rod is normally seated in a keeper notch 27 formed on the extreme upper end or projection 28 of the extension 29 on the upper end of the intermediate coupling member 24. This part 29 is formed with left hand screw threads which 15 tap into the correspondingly threaded lower end of the upper member 31 of the coupling or jointing means. The part 31 has its upper socketed end 32 formed with right hand screw threads to receive the correspondingly threaded lowermost 20 section 33 of the sucker rod, that is, that portion of the rod above the special separable joint means. It will be noticed that this upper special member 31 is also formed with a central bore 34 and diametrically opposite grooves 35 which form 25 keyways for the projecting ends of the key or latch head 26. The lower end of the latch rod 25 projects down into the screw-threaded portion of the sleeve 17 where it is secured by a pin to a spring accommodation socket or cup 36. The 30 spring is indicated at 37 and is a suitable coil spring and surrounds the lower end of the stem or rod 25, one end resting in the cup 36 and the other end bearing against the plug-like extension 23. The result is that this spring is normally 35 tensioned to keep the latch in the locking position shown in Figure 8, at which time the head 28 is located in the notch 27 with the ends thereof projecting into the keyways 35. This locks the left hand screw-threaded parts temporarily or 40 normally together, so that when the parts are as shown in Figure 8 the entire sucker rod can be bodily turned in a direction toward the right, that is clockwise, without affecting the left handed screw-threaded connection, that is, the 45 features 29 and 30.

Whenever it is necessary to pull the pump rod, that is, the sucker rod assembly above the joint 16, which is necessary when the valve becomes stuck, it is obvious that the entire string including sections 15 is turned bodily in a right hand direction which in effect tightens all of the threaded connections between the respective sections or parts 15. By referring to Figure 8, it will be observed that while this rotary movement 55 is carried out, the joint 16 feeds down in relation to the trip or thrust rod 20. That is to say, the sleeve 17 threads down on the head 19. In due time the head 19 comes into contact with the spring-pressed cup 36 and presses the latch rod 60 25 upwardly. At a predetermined time the locking or connecting latch head 26 rides out of the keeper notches 27. Continued rotation of the sucker rod in the same direction thus unscrews the part 31 from the part 24, as is obvious, allowing the sucker rod to break from the lower portion thereof, as shown for example in Figure 2, so that it can be pulled out from the casing. In 65 this way all of the sections appearing above the joint 16, as shown in Figure 2, can be retrieved in 70 an obvious and reliable manner.

In order that the succeeding claims may be more satisfactorily interpreted, it may be stated that the major portion of the sucker rod assembly above the special releasing joint 16 can be 75 conveniently referred to as the upper portion of

the pump rod or removable part thereof. The part below the joint 16, which is relatively stationary because of binding or anchorage from sticking, may be either referred to as the non-removable or lower part of said pump rod. The 5 joint 16 between the two parts is an automatically releasable operating connection.

It is thought that the description taken in connection with the drawings will enable a clear understanding of the invention to be had. 10 Therefore, a more lengthy description is thought unnecessary.

While the preferred embodiment of the invention has been shown and described, it is to be understood that minor changes coming within 15 the field of invention claimed may be resorted to if desired.

I claim:

1. In a structure of the class described, a sucker rod construction including a plurality of complementary sections joined by right hand screw-threaded joints, an upper coupling member carried on the lowermost section of said sucker rod construction and provided with an internal screw-threaded socket, the threads being left 20 handed, a second longitudinally spaced axially aligned lower coupling member in the form of a sleeve internally screw-threaded with right hand threads, a trip device comprising a rod having a screw-threaded head threaded into said sleeve, a 25 jointing member between said upper and lower coupling members, said jointing member being longitudinally bored and having a threaded extension at its lower end, the threads of which are right handed and tapped into the right hand 30 threads in said sleeve, said jointing member being provided at its upper end with a similar extension having left hand threads tapped into said correspondingly threaded socket, said upper coupler member being provided with a central bore 35 and keyway, a reciprocatory spring-pressed latch member mounted in the bore in said jointing member and provided at its upper end with a cross-head normally connected with said jointing member, whereby to permit said parts to be 40 separated automatically under predetermined rotational conditions.

2. In a safety joint for a sucker rod assembly of the class described, an intermediate jointing member longitudinally bored and provided at its 50 upper end with a screw-threaded extension, the threads of which are left handed, said extension being provided with a projection having keeper notches formed therein, the lower end of said member being provided with a screw-threaded 55 extension, the threads of which are right handed, a rod mounted for sliding in said bore and provided at its upper end with a cross-head located in said notches, spring retention means connected to the lower end of said rod to hold the 60 cross-head in said notches, a sleeve having right hand threads threaded connected to the lower extension on said jointing member, a thrust rod having a right hand screw-threaded head mounted in said sleeve for engagement with the spring-65 equipped end of said latch rod, an upper coupling member having right hand threads at its top connectible with an adjacent section of the sucker rod assembly, and having a screw-threaded socket at its lower end, the threads of which are 70 left handed and connected with the extension on the adjacent upper end of said jointing member, the intermediate portion of said upper coupling member being provided with diametrically opposite keyways into which the end portions of said 75

head project to normally lock the several parts of the coupling together, said head being releasable from the keeper notches upon threading the sleeve down on the head of said trip rod in the manner and for the purposes described.

3. As a component part of an assemblage of the class described, a sucker rod and traveling valve jointing assembly comprising a jointing member longitudinally bored and provided at its upper end with a screw-threaded extension, the threads of which are left-handed, said extension terminating with a projection having keeper notches, the lower end of said jointing member being provided with a screw-threaded extension, the threads of which are right-handed, a latch rod slidably mounted in said bore and provided at its upper end with a cross-head located in said

keeper notches, the ends of said head extending outwardly beyond said notches, the lower end of said rod extending downwardly beyond the adjacent screw-threaded extension, an abutment on the lower end of said rod, a coiled spring surrounding the lower end portion of the rod and bearing at its lower end against said abutment and at its opposite end against the adjacent screw-threaded extension to hold said cross-head in said keeper notches, a sleeve having internal right-hand screw-threads separably joined to the lower extension on said jointing member, and a trip rod having a screw-threaded portion threaded into said sleeve in a position to engage the spring-equipped end of said latch rod in the manner and for the purposes described.

WILLIAM H. STIGALL.
